**BOAT BOW PLATE WITH BULLNOSE AND
BOOM PIVOT**

John D. Cornwell, Jr., Henry County, near Stockbridge, Ga., assignor of fifty percent to Patrick F. Henry, Atlanta, Ga.

Filed June 10, 1968, Ser. No. 735,902
Int. Cl. B63b 21/04

U.S. CL. 114—218

1 Claim

ABSTRACT OF THE DISCLOSURE

A bow plate for boats having a top plate which can be attached to the deck of a boat such as a sailboat near the bow and having a vertical plate welded thereto with aligned, spaced holes along the top thereof and a bullnose ring welded to the front tip of the vertical plate and also to the deck plate so that a line such as a towline can be led to the bullnose. The bottom portion of the vertical plate is removed leaving a triangular space facilitating handling of lines. The back of the deck plate supports a 360° rotational jib club boom pivot. The composite device provides a very good means of running a line through the bullnose as well as a jib club boom attachment and also a selective position in the holes on the vertical plate for other fittings. The deck plate may be held in place by a back-up plate underneath the deck through which is inserted bolts.

BACKGROUND OF THE INVENTION

Field of the invention

Marine hardware and particularly bow plates and boom pivots.

Description of the prior art

The known prior art for a similar purpose includes a bow cleat and also a separate jib club boom pivot. There is no known prior art which includes a bullnose with a vertical plate and a deck plate all secured together as by welding plus optionally the jib club boom pivot on the opposite end from the bullnose. This provides a very good way of running a line for towing or the like as well as giving selective fittings for attachment of the jib club boom and other devices.

SUMMARY OF THE INVENTION

A composite marine fitting for sailboats or the like comprising a deck plate, a vertical plate mounted on the deck plate, a ring attached to the deck plate and extending transversely across said vertical plate, said vertical plate having openings spaced therealong and there being a space beneath said vertical plate and behind said ring.

BRIEF DESCRIPTION OF THE DRAWINGS

Other and further objects and advantages of my invention will become apparent upon reading the following specification taken in conjunction with the accompanying drawings, in which:

FIG. 1 is a top plan view of the present device.

FIG. 2 is a side elevation view of the present device in place on a boat most of which is broken away.

FIG. 3 is a perspective view of the present device disassembled from the back-up plate.

DESCRIPTION OF A PREFERRED EMBODIMENT

Referring initially to FIG. 3, the overall device is des-

2

gnated by reference numeral 10 and comprises a deck plate 12 which is a flat, metal plate of stainless steel, chrome plated steel or the like, having attachment openings 14 therethrough. Plate 12 is tapered at the front with angular edges 16 converging toward the front tip 18 and is similarly tapered at the rear with converging edges 20 converging to a rear tip 22.

A vertical plate 24 is welded in place at 25 and has a slanted rear edge 30 and a substantially straight top edge 32 curved at the front and from which extends the slanted front edge 34 forming a triangular space 36 with plate 12. A bullnose plate 42 is welded at 44 to vertical plate 24 and at 46 to deck plate 12 and is inclined rearwardly at a 30 degree angle as shown in FIG. 2. Ring 42 is welded at 44 adjacent the front tip 46 of plate 24. Top edge 42 is 45 degrees from the rearwardly inclined edge 30 and the edge 34 is 20 degrees to the deck plate 12, all as shown in FIG. 2.

A pivot means which may be in the form of a jib club boom pivot designated generally by reference numeral 50 is pivotally mounted on a pivot pin 52 extending through plate 28 near the rear or aft end thereof. Boom pivot 50 comprises vertical, spaced plates 54, 56 connected to a bottom plate 58 which together form a U-shaped bracket. The boom pivot 50 will pivot or swivel in a 360° arc in either direction and there are spaced holes 60 therein in horizontal alignment to permit the insertion of a pin or any other fitting or member.

The device 10 may be fastened to a boat represented diagrammatically by reference numeral 64 and having a deck 66 which may be constructed from fiberglass, plywood or other material. Deck plate 28 is placed flat on the deck as shown in FIG. 2 and a backup plate may be used with unreinforced decks and is designated generally by reference numeral 68 and comprises a flat plate with a top surface 70 having spaced holes 72 matching and corresponding with the holes 14 in the plate 12. Stainless steel screws or other fasteners 76 may be used through the respective holes 14 and 72 with nuts 78 for securing the entire device 10 in place on the boat 64.

It should be noted that the angle of the rear edge 30 of the vertical plate 24 provides a triangular space 80 which allows clearance and free movement of the boom pivot as well as providing sometimes needed space for working lines and fittings. Also, the space 38 beneath the front edge 34 of the vertical plate 24 and behind the bullnose ring 42 provides needed space for lines or fittings. The entire arrangement is very practical and needed for use as a bow plate on sailboats and other boats particularly those of the range through 16 feet. Such a fitting completely can be just a little over five inches in total length and, for example, the bullnose ring can be just under one inch in outside diameter. By using a fusion weld at weld line 26 to attach the vertical plate 24 sufficient strength is provided and manufacture is sufficiently economical. Also, the use of a fill weld to attach the bullnose at weld points 44, 46 is economically feasible from the standpoint of manufacture and provides sufficient strength.

While I have shown and described a particular embodiment of my invention together with suggested operation thereof and also have mentioned some typical dimensions and angles, this is by way of illustration only and does not constitute any sort of limitation on the scope of my invention since various alterations, changes, deviations, eliminations, substitutions, additions, revisions and depar-

tures may be made in the form shown and in the use described without departing from the scope of my invention as defined in the interpretation of the appended claim.

What is claimed:

1. In a combination fitting for a boat bow or the like:
  - (a) a deck plate to be superposed on a flat portion of a deck,
  - (b) an upstanding plate member on said deck plate having attaching means thereon,
  - (c) a continuous member adjacent the end of the deck plate and the upstanding plate and having an opening therethrough, said member, having the plane thereof transversed to the upstanding member and the deck plate,
  - (d) and a jib club boom pivot bracket spaced from 15

said continuous member, said pivot bracket having spaced attachment portions with holes therein.
